W. G. KRAFT.

SALT AND PEPPER SHAKER.
APPLICATION FILED FEB. 25, 1911

1,007,294.

Patented Oct. 31, 1911.

UNITED STATES PATENT OFFICE.

WESLEY G. KRAFT, OF MARION, KANSAS.

SALT AND PEPPER SHAKER.

1,007,294.

Specification of Letters Patent. Patented Oct. 31, 1911.

Application filed February 25, 1911. Serial No. 610,925.

To all whom it may concern:

Be it known that I, WESLEY G. KRAFT, citizen of the United States, residing at Marion, in the county of Marion and State of Kansas, have invented certain new and useful Improvements in Salt and Pepper Shakers, of which the following is a specification.

This invention relates to condiment holders, and has special reference to a combined pepper and salt shaker.

An object of the present invention is to produce a device adapted to contain both the pepper and the salt, and a device which is provided with thumb levers, or the like, for independently turning the perforated revolving caps closing the holders of the device to release either the pepper or the salt, or both as desired.

A further object of this invention is to produce a light, simple, and compact device adaptable to the hand, and one which can be easily operated by the thumb of the hand supporting the device.

For a full understanding of the invention and the merits thereof and also to acquire a knowledge of the details of construction, reference is to be had to the following description and accompanying drawings, in which:

Figure 1 is a perspective view of the improved shaker; Fig. 2 is a longitudinal central section taken through the shaker in an inverted position; Fig. 3 is a transverse central section taken through the same. Fig. 4 is a detail perspective view of the support for the levers of the shaker.

Corresponding and like parts are referred to in the following description and indicated in all the views of the drawings by the same reference characters.

Referring to the drawings the reference numerals 10 and 11 designate a pair of holders or receptacles which are spaced apart and held in such position by companion plates 12. The lower ends of the receptacles or holders 10 and 11 are provided with concaved bottoms which are centrally apertured for the reception of stoppers 13. The material placed in the receptacles 10 and 11 is inserted through the bottom by removing the stoppers 13. The upper ends of the receptacles 10 and 11 are each formed with an annular outwardly pressed bead 14 which is spaced slightly below the upper edge of each of the recep-

tacles. A stationary cap 15 is fitted over the upper end of each of the receptacles 19 and 11 and is formed with a depending flange 16 having a bead or rib 17 fitting over the bead 14. The cap 15 is adapted to be fitted upon the receptacle so that it will not rotate. Each of the receptacles is provided with an outer or rotary cap 18 having a depending flange 19 provided with an outwardly pressed rib or bead 20 engaging somewhat loosely over the rib or bead 17 so as to admit of the rotation of the cap 18 and at the same time to seal the space between the caps 15 and 18. A bottom plate 21 is disposed between the lower ends of the receptacles 10 and 11 and is fastened at its sides upon the lower edges of the companion plates 12.

Arranged between the receptacles 10 and 11 is a support 22 between the arms of which are pivotally mounted thumb levers 23 and 24. The thumb levers are of L-form, the long arms thereof being provided midway of their ends with oppositely extending studs 25 loosely engaging through the adjacent walls of the support 22 for pivotally supporting the thumb levers. With reference to Fig. 4 of the drawing it will be noted that the support 22 is formed of a strip of metal bent upon itself and having its free ends turned over to provide two U-shape pockets for the reception of the levers 23 and 24. The studs 25 carried upon the levers 23 and 24 engage through the walls of the opposite pockets and in the opposite ends thereof. It will be noted from the drawing that the lever 23 is relatively short so as to space the outstanding short arms of the levers from each other and to distinguish them one from the other. The outer ends of the long arms of the levers 23 and 24 loosely engage in thimbles 26 provided upon the inner opposite sides of the rotary caps 18. A top plate 27 closes the space between the receptacles 10 and 11 and is of such shape that it snugly engages between the receptacles and meets the upper edges of the companion plates 12. Spaced slots 28 are formed in the top plate 27 through which the upper extremities of the levers 23 and 24 extend to enter the thimbles 26. The upper companion plate 12 is provided with spaced slots 29, one being disposed in advance of the other, to receive the outer ends of the short arms of the levers 23 and 24. Buttons 30 are mounted

upon the outer ends of the short arms of the levers 23 and 24 and bear suitable configurations for designating the material disposed within the respective receptacles 10 5 and 11, as for instance, S meaning salt, and P meaning pepper. The inner companion plate 12 carries a pair of helical springs 31 which are attached at their outer ends to the long arms of the thumb levers 23 and 10 24 above the pins 25. The springs 31 are employed for normally holding the thumb levers 23 and 24 against the lower ends of the slots 28.

The operation of the device is apparent, 15 since the device is grasped in one hand and the thumb of the hand is placed upon either one of the buttons 30. When the button is depressed, for instance the button marked S, the thumb lever 23 is swung down within 20 the slot 29 and the upper or outer extremity of the thumb lever is moved through the slot 28 and carries therewith the thimble 26, rotating the cap 18. The caps 15 and 18 are provided in the usual manner with a plurality 25 of apertures which are adapted to register upon the rotation of the cap 18 to admit of the escape of the contents of the adjacent receptacle or holder. When the button 30 is released the spring 31 which is attached to 30 the thumb lever 23 retracts the same and closes the cap 18. In a similar manner the opposite holder 10 may be opened to admit of the escape of the pepper contained therein.

It is of course understood that this device 35 may be used in connection with other substances than salt and pepper as the apertures through the caps 15 and 18 may be made in any size desired.

Having thus described the invention, what 40 is claimed is:

1. A device as specified including spaced 45 holders, companion plates engaging against the sides of the holders, spaced arms carried between the holders midway of their ends, thumb levers hinged between the arms and having the short arms thereof projecting out 50 through the adjacent companion plate, fixed perforated caps carried upon the holders, rotary perforated caps carried upon said fixed 55 caps, thimbles arranged against the sides of the rotary caps and having connection with the thumb levers, and buttons disposed upon the extremities of the short arms of the thumb levers for depressing the same.

2. A salt and pepper shaker including 60 spaced receptacles, companion plates engaging against the sides of the receptacles to connect the same, rotary caps carried upon the upper ends of the receptacles for controlling the passage of the salt and pepper

therefrom, and thumb levers carried by the companion plates and having connection to the rotary caps for opening the same.

3. A condiment holder including spaced 65 receptacles, companion plates joining the receptacles, spaced arms carried between the receptacles midway of their ends, thumb levers hinged upon the arms and being of L-form having the short arms thereof extending through one of the companion plates 70 and its long arms extending up between the receptacles, movable caps carried upon the receptacles for controlling the passage of material therethrough, and thimbles carried against the inner sides of the caps and having loose connection with the adjacent extremities of the thumb levers.

4. A condiment holder including spaced 75 receptacles, companion plates joining the receptacles, end plates engaging between the 80 receptacles and across the opposite edges of the companion plates, L-shape thumb levers hinged between the receptacles and having their opposite arms extending through one of the companion plates and one of the end 85 plates, buttons carried upon the ends of the thumb levers and extending through the companion plates, caps slidably mounted upon the upper ends of the receptacles for opening and closing the same, and thimbles 90 fixed against the inner sides of the caps and loosely engaging over the adjacent arms of the thumb levers.

5. A condiment holder including spaced 95 receptacles, companion plates engaging across the sides of the receptacles to join the same, end plates engaging between the ends of the receptacles and across the edges of the companion plates, spaced arms disposed between the companion plates midway of the ends 100 of the receptacles, L-shape thumb levers hinged upon the arms and having their opposite extremities extending through one of the companion plates and one of the end 105 plates, slidable caps carried upon the adjacent ends of the receptacles, thimbles disposed against the inner opposite sides of the caps and loosely engaging over the adjacent extremities of the thumb levers, and buttons carried upon the opposite ends of the thumb 110 levers and bearing distinguishing marks to indicate the cap to which the same is connected.

In testimony whereof, I affix my signature in presence of two witnesses.

WESLEY G. KRAFT. [L.S.]
